US00D858919S

(12) **United States Design Patent** (10) **Patent No.:** **US D858,919 S**
Payne et al. (45) **Date of Patent:** **** Sep. 3, 2019**

(54) **GUITAR CLEANING CLOTH**

(71) Applicants: **Peggy Murphy Payne**, Queen Creek, AZ (US); **Timothy Evander Payne**, Queen Creek, AZ (US)

(72) Inventors: **Peggy Murphy Payne**, Queen Creek, AZ (US); **Timothy Evander Payne**, Queen Creek, AZ (US)

(73) Assignee: **Peggy Murphy Payne**, San Tan Valley, AZ (US)

(**) Term: **15 Years**

(21) Appl. No.: **29/561,786**

(22) Filed: **Apr. 20, 2016**

(51) LOC (12) Cl. **07-05**

(52) U.S. Cl. **D32/40**
USPC ....
